(57) **CLAIM**

The ornamental design for a junction box, as shown and described.

DESCRIPTION

FIG. 1 is a right view of the first embodiment of a junction box, showing my new design;

FIG. 2 is a bottom view of the junction box.

FIG. 3 is a left view of the junction box.

FIG. 4 is a front view of the junction box.

FIG. 5 is a top view of the junction box.

FIG. 6 is a rear view of the junction box.

FIG. 7 is a front right perspective view of the junction box.

FIG. 8 is a front left perspective view of the junction box.

FIG. 9 is a top rear perspective view of the junction box.

FIG. 10 is a bottom rear perspective view of the junction box.

FIG. 11 is a right view of the second embodiment of a junction box;

FIG. 12 is a bottom view of the junction box.

FIG. 13 is a front view of the junction box.

FIG. 14 is a top view of the junction box.

FIG. 15 is a rear view of the junction box.

FIG. 16 is a left view of the junction box.

FIG. 17 is a top rear perspective view of the junction box.

FIG. 18 is a bottom rear perspective view of the junction box.

FIG. 19 is a front right perspective view of the junction box.

FIG. 20 is a front left perspective view of the junction box.

FIG. 21 is a right view of the third embodiment of a junction box;

FIG. 22 is a bottom view of the junction box.

FIG. 23 is a front view of the junction box.

FIG. 24 is a top view of the junction box.

FIG. 25 is a rear view of the junction box.

FIG. 26 is a left view of the junction box.

FIG. 27 is a top rear view of the junction box.

FIG. 28 is a bottom rear view of the junction box.

FIG. 29 is a front right view of the junction box.

FIG. 30 is a front left view of the junction box.

FIG. 31 is a bottom rear exploded view of the junction box.

FIG. 32 is a front left exploded view of the junction box.

FIG. 33 is a front right exploded view of the junction box; and,

FIG. 34 is a top rear exploded view of the junction box.

In the drawings, the broken lines are for the purpose of illustrating environment only and form no part of the claimed design.

1 Claim, 34 Drawing Sheets
